UNITED STATES PATENT OFFICE.

WILLIAM KANE, OF PHILADELPHIA, PENNSYLVANIA.

BOILER OR HEATER.

1,215,031.

Specification of Letters Patent.

Patented Feb. 6, 1917.

Application filed October 16, 1916. Serial No. 125,940.

To all whom it may concern:

Be it known that I, WILLIAM KANE, a citizen of the United States, residing at Philadelphia, in the county of Philadelphia and State of Pennsylvania, have invented certain new and useful Improvements in Boilers or Heaters, of which the following is a specification.

My invention consists of an improved 10 boiler or heater, and is particularly servicable where a low pressure capacity boiler or heater is required.

Boilers are generally made circular or nearly so and to attempt to cast the tubes 15 in a cast iron boiler, has prior to my invention, been practically impossible where the body portion has been cast in one piece.

One object of my invention therefore is to provide a boiler or heater of the above 20 described type which is cast in two substantially similar sections, said sections being joined together in such manner as to render the boiler or heater of simple construction. Another object is to construct 25 my improved boiler or heater in such manner that it may be easily and quickly cast.

A further object of my invention is to provide a boiler or heater in which gas or other hydro-carbon fuel may be used econ- 30 nomically as the heating medium.

Another object of my invention is to provide a heater or boiler in which the tubes, used for conveying the products of combustion, will be formed by the assembling of 35 the above noted sections, thus doing away with the requirement of casting complete tubes directly in the body portion of a boiler or heater.

A still further object of my invention is 40 to provide a heater or boiler which will be of comparatively compact construction and will be extremely durable.

These objects, and other advantageous 45 ends which will be described hereinafter, I attain in the following manner, reference being had to the accompanying drawings in which—

Figure 1 is a front elevation of a boiler 50 or heater made in accordance with my invention.

Fig. 2 is a sectional elevation taken on the line *a—a* of Fig. 1.

Fig. 3 is a sectional elevation taken on the line *b—b* of Fig. 2.

Fig. 4 is a plan view of my improved 55 boiler or heater with the top cover removed.

Fig. 5 is a plan view of similar nature to Fig. 4 showing a modified shape of boiler made in accordance with my invention, and

Fig. 6 is an enlarged fragmentary view 60 showing one form of section-coupling joint which I may employ.

Referring to the drawings, 1 and 2 represent the respective sections comprising the body portion of my improved boiler or heater 65 and as illustrated in Figs. 1 to 4 inclusive are each substantially semi-circular in cross section.

The sections 1 and 2 are provided with integral downwardly extending flanges 3 and 70 4 respectively. These flanges preferably are flared to form a hollow base 5. The flange 4 has an opening 6 for the insertion of a gas burner 7 or other heat-supplying means, and a door 8 is provided to form a 75 closure for said opening, said door in the present instance having a substantially vertical slot 9 designed to permit the insertion of a feed pipe 10, however, it will be understood that any form of feed pipe or fuel 80 supplying means may be used to extend into the base 5 and form the heating agent for the boiler.

A bottom plate or drip pan 11 forms the direct support for the bottom edges of the 85 flanges 3 and 4 of the base 5, thus providing a proper mounting.

Each of the sections 1 and 2 is provided with channels or recesses 12 which register with each other as clearly shown in Figs. 3 90 and 4. These recesses are produced by hollow extensions and provide flues or tubes which convey the products of combustion from the base 1 to a chamber 13 provided at the top of the sections by a hood or cover 95 14, the latter being supported by the upper edge portions of the sections 1 and 2. One of said hollow extensions of each of the sections 1 and 2 is shorter than the others and centrally located so that when the sections 100

are placed together as shown in Fig. 4, a space will be provided between them for a purpose hereinafter described, while the other of said hollow extensions of each section respectively contact with each other.

It will, of course, be understood that each of the sections 1 and 2 are hollow and may be filled or partially filled with water which will become heated by the passage of the 10 products of combustion upwardly through the flues provided by the channels 12.

I preferably secure the sections 1 and 2 together with right and left hand threaded nipples 15 and 16, the opposite ends of the 15 nipples fit within tapped openings in said central hollow extensions, each of said nipples being provided with hexagonal nuts intermediate their ends which are located within the space provided by the oppositely 20 disposed central hollow sections, so that the turning of said nuts will tend to draw the sections 1 and 2 together and securely hold them in position.

Each of the sections 1 and 2 is provided 25 with an overlapping lip 17 which forms a closure adjacent the outer edges for the parting which exists between the sections 1 and 2. It will thus be understood that each of the nipples 15 and 16 forms a coupling for the sections and also forms a 30 means of communication between the interior of said sections as clearly shown in Fig. 2.

A heater or boiler constructed in accordance with my invention can be easily manufactured and assembled, is efficient in service, and is durable.

In the modification shown in Fig. 5, I have shown the boiler sections 18 and 19 half 40 elliptical in cross section and joined to form an elliptical boiler. With the exception of the shape of these sections, the construction is similar to that described in connection with Figs. 1 to 4 inclusive and I have therefore given like parts similar reference numerals.

In Fig. 6, instead of having the lips 17 forming the seal at the outer edges, I provide a tongue and groove connection as 50 shown at 20 to form a seal joint, and it will be noted that if desired the joint connection between the lips 17 and the adjacent sections may be calked or plastered prior to the joining together of said sections so as to form 55 a perfect seal. In a similar manner, plaster or other sealing material may be provided in addition to the tongue and groove connection as shown at 20 in Fig. 6.

While I have described my invention as 60 taking a particular form, it will be understood that the various parts of my invention may be changed without departing from the spirit thereof, and hence I do not limit myself to the precise construction set forth, but

consider that I am at liberty to make such 65 changes and alterations as fairly come within the scope of the appended claims.

Having thus described my invention, what I claim as new and desire to secure by Letters Patent is:

1. A boiler or heater including two hollow cast sections having hollow registering extensions forming flues, certain of said hollow extensions being shorter than others and providing a space between their adjacent 75 ends, nipples connecting said latter ends of the extensions and having wrench engaging portions located within said space, the other of said extensions of each section being designed to engage corresponding extensions 80 on the other section, substantially as described.

2. A boiler or heater including two hollow cast sections having hollow registering extensions forming flues, certain of said hollow extensions being centrally located and shorter than others and providing a space between their adjacent ends, nipples connecting said latter ends of the extensions and having wrench engaging portions located within said space, the other of said extensions of each section being designed to engage corresponding extensions 85 on the other section, substantially as described.

3. A boiler or heater including two hollow cast sections having hollow registering extensions forming flues, certain of said hollow extensions being shorter than others and providing a space, nipples connecting said latter extensions and having a wrench engaging portion located within said space, the other of said extensions of each section being designed to engage corresponding extensions 95 on the other section, and a detachable hood forming a chamber which communicates with the top of said flues, substantially as described.

4. A boiler or heater including two hollow cast sections having hollow registering extensions forming flues, certain of said hollow extensions being shorter than others and providing a space between their adjacent ends, nipples connecting said latter ends of the extensions and having wrench engaging portions located within said space, the other of said extensions of each section being designed to engage corresponding extensions 110 on the other section, each of said sections having an integral flanged skirt at the bottom providing a hollow base closure in direct 115 communication with said flues, substantially as described.

5. A boiler or heater including two hollow cast sections having hollow registering extensions forming flues, certain of said hollow extensions being shorter than others and providing a space, nipples connecting said latter extensions and having a wrench en-

1,215,031

gaging portion located within said space, the other of said extensions of each section being designed to engage corresponding extensions on the other section, a hood forming a chamber which communicates with the top of said flues, and means providing a hollow base communicating with the bottom of said flues, substantially as described.

In testimony whereof I have signed my name to this specification in the presence of 10 two subscribing witnesses.

WILLIAM KANE.
